(57) **CLAIM**

The ornamental design for a warp drive for aerospace vehicle, as shown and described.

DESCRIPTION

FIG. 1 is a right side elevational view of a warp drive engine module for an aerospace vehicle, showing my new design.

FIG. 2 is a top plan view thereof.

FIG. 3 is a left side elevation thereof.

FIG. 4 is a bottom view thereof.

FIG. 5 is a rear elevational view thereof; and,

FIG. 6 is a front elevational view thereof.

The plasma conduit and plasma drive node in FIG. 1 and the circular attachment features in FIGS. 5 and 6 are shown in broken line and do not form part of my design.
